FOLLOW-UP ACTUATING MECHANISM FOR
PRESSING MACHINESErnest Davis, Syracuse, N. Y., assignor to The
Prosperity Company, Inc., Syracuse, N. Y., a
corporation of New YorkApplication February 23, 1929, Serial No. 342,222
Renewed November 12, 1931

22 Claims. (Cl. 68—9)

This invention relates to garment, ironing and laundry presses, and an object is to attain uniform pressure on the work between the press jaws even though the pad on the buck gradually yields 5 and gives away or thins down due to usage.

In laundry and garment pressing machines, the padding on one or both of the pressing elements or jaws gradually becomes thinner in the use 10 of the machine. Temporary thinning or compression results when each pad compresses during each operation of the press, but the pad thinning referred to here is permanent and results from continued use, so that it gets a permanent set which gradually increases with additional use 15 of the press. This thinning of the padding causes the pressure between the pressing elements to vary or to continually decrease gradually. Most pressing machines have manually operable adjusting means for compensating for the thinning or permanent compression of the padding and the adjustment depends entirely on the will of 20 the operator who may or may not make the adjustment when it should be made.

This invention has for its object a particularly 25 simple and efficient actuating mechanism by which a substantially uniform pressure is delivered regardless of the thickness of the work or of the amount of compression of the padding used on one or both of the pressing elements; and more particularly an actuating mechanism 30 which has an automatic follow-up action to compensate for the decrease in thickness of the padding due to the permanent setting of the padding.

The invention consists in the novel features and 35 in the combinations and constructions herein-after set forth and claimed.

In describing this invention, reference is had 40 to the accompanying drawings in which like characters designate corresponding parts in all the views.

Figure 1 is a side elevation, partly broken away, 45 of a pressing machine embodying one form of this invention.

Figure 2 is a fragmentary rear elevation looking 50 to the left of Figure 1.

Figure 3 is an enlarged sectional view through 55 the joint or knee of a toggle employed to open and close the press.

Figures 4 and 5 are fragmentary views, partly 50 in section, illustrating a modified form of the mechanism shown in Figure 1.

Figure 6 illustrates an additional modified form.

Figure 7 is an end view, partly in section, of the 55 structure shown in Figure 5.

This pressing machine comprises, generally, co-

operating pressing elements, or press jaws, one of which is movable toward and from the other, an actuator or motor means, and motion transmitting means between the actuator and the movable element. The motion transmitting means 5 comprise driving and driven members forming initial closing means and normally idle differential or jaw compressing means connecting them and arranged to act when the movable element of the press engages and encounters the resistance 10 of the other element. Through that part of the movement of the movable element, prior to its engagement with the other pressing element or jaw or during the closing movement of the press, said members act in one relation to transmit the 15 motion of one member directly to the other and upon the movable element contacting with the other element, the members coact in another relation through the differential means or reduction leverage. These two actions permit the driving 20 member to move at a greater speed and through a greater distance than the driven member and thereby translate the greater movement thereof 25 into a movement of lesser extent and with more power or increased pressure when the movable element moves under final pressure and is compressing the padding.

I have here shown my invention as embodied 30 in a conventional type of pressing machine comprising upper and lower pressing elements or jaws as the head 1 which is movable toward and from a stationary buck 2 suitably mounted on a frame 3. The head is supported in the usual manner at the front end of a yoke lever 4 which is pivoted 35 between its ends at 5 to a standard 6 rising from the frame.

The press here illustrated is power actuated 40 through motor means as by a suitable single motor comprising a cylinder 7 and a piston therein, the rod 8 of which may be considered the actuator. Insofar as this invention is concerned, the press may be actuated by any suitable motor means or by foot power, but it is better adapted 45 for power operated presses.

The flow of motive fluid as air to and from the 50 cylinder 7 is controlled in any suitable manner as by valves which are operated by a push button 9 and a release lever 10. The valves and the controls therefor form no part of this invention.

The motion transmitting means between the 55 actuator 8 or motor means 7 and the head 1, in addition to the yoke lever 4, comprises driving and driven members forming initial closing means and a normally idle differential or jaw compressing means carried thereby. The driving and driven

members are here shown as toggle links 11 and 12 pivoted respectively at 13 and 14 to the base of the frame and to the rear arm of the yoke lever 4 and pivotally connected together. The pivot 5 also cooperates with a reduction, differential mechanism or jaw compressing means as will be described. The actuator, or piston rod 8 is pivoted at 15 to the driving link 11.

The reduction gearing, differential mechanism, 10 or jaw compressing means here illustrated comprises a cam 16 associated with one of the links and a follower or roller 17 movable along the cam and associated with the other link, the cam 16 extending at an angle to the direction of the 15 thrust or lifting movement of the toggle link 12 or in the direction of the movement of the joint of the toggle. In other words, the cam 16 is eccentric to the pivot 13 with its left end a greater 20 distance from the pivot 13 than its right end, as viewed from the side of the press in Figure 1.

Means are provided for holding or locking the cam 16 and the follower 17 from relative movement during the straightening of the toggle 11—12, until the head encounters the resistance 25 of the buck or pad thereon when reaching preliminary closed position. This means comprises a shoulder or roller 12^a carried by the link 12 which thrusts against the link 11 together with a gear wheel 18 mounted on one side of the follower 30 17 and meshing with a rack 19 extending along the slot 16 and also includes means for normally locking the gear wheel 18 from rotation. As seen in Figure 3, this differential locking means is a brake wheel 20 also mounted on and movable 35 with the follower 17 and gear wheel 18 and a brake member 21 normally engaged with the wheel 20, the brake member being operable out of its holding or braking position by the reaction of the head when it encounters the buck 2.

40 The toggle link 12 is formed of two sections arranged end to end with a compression spring or other yielding means 22 between them, as shown in Figure 3, and the brake 21 is carried by and movable with the section of the link 12 which is connected to the yoke lever 4.

45 The roller 12^a above referred to is carried at the lower end of the lower section of the link 12 and normally thrusts against the end wall 12^b of the wall of the cam slot 16 (see Figure 1) to prevent movement of the cam along the slot when the initial starting impulse is given to the toggle links 11, 12 to overcome the inertia of the stationary head and start it in motion. As the links 50 11, 12 initially straighten, the roller 12^a rides out of engagement with the end wall 12^b and thereafter the follower 17 and the cam 16 are held from relative movement by the brake wheel 20 and brake member 21.

55 Obviously, when the toggle links 11, 12 are actuated toward a straight line, the cam follower 17 will be held from movement along the slot 16 so that the toggle links will act solely as a toggle. When, however, the head 1 presses against the buck 2 with a predetermined pressure, the spring 60 22 between the sections of the link 12 will be compressed, that is, the link 12 will shorten, moving the brake member 21 out of coaction with the brake wheel 20, thus permitting the follower 17 to move along the slot 16 or rather permitting the 65 slot to move along the follower. During such movement, the cam 16 will thrust the link 12 upwardly and further press the head 1 against the buck 2 during rearward movement of the link 11 relatively to the link 12, the amount of relative 70 movement of the cam follower 17 and slot 16 de-

pending upon the amount of padding on one or the other of the pressing elements is compressed.

Means is also provided for locking the initial closing means or particularly the driven member or link 12 of the toggle from swinging movement 5 while the reduction or differential mechanism is acting and this locking means is controlled by the compression of a resilient mounting such as the padding on the buck 2.

As shown in Figure 1, a locking bolt 23 extends 10 vertically through the buck and into the padding and has a head 24 at its upper end underlying the top surface of the pad. The lower end of the bolt coacts with a rack 24^a connected by a link 25 to the toggle link 12 but the bolt 23 is held 15 normally in its retracted position, or out of engagement with the rack by a spring 26 so that the rack moves rearwardly as the press closes. When the pad compresses, it moves the bolt into engagement with the rack and thus holds link 12 in its 20 place or against pivotal movement while link 11 moves rearwardly to exert upward thrust against the link 12. Obviously, this operation can take place only after the toggle links 11 and 12 have moved toward straightened position far enough 25 to bring the head 1 down on the buck 2 where it starts to compress the pad. The rack 24^a is slidably mounted so as to move rearwardly while the toggle links are straightening.

30 It will be noted that the initial closing means of the motion transmitting means or the toggle links 11 and 12 are moved to preliminary closed position without the toggle links reaching straightened position or the limit of their extent of movement. In other words, the toggle or 35 initial closing means has a greater extent of movement than is necessary to bring the jaws 1 and 2 together. With this construction provision is made for mashing of the pad on the buck 2 or a permanent set being sustained by the resilient mounting, in that the toggle can continue to close until the jaws are preliminarily engaged, irrespective of the amount of mashing which has taken place in the pad. The locking means is operated or controlled by the jaws engaging and 40 thereby prevents further operation of the toggle or initial closing means of the motion transmitting means whereupon the jaw compressing means or differential mechanism is set into operation.

50 In Figures 4 and 5, the locking bolt 27 is shown as operated by a diaphragm 28 in a diaphragm chamber 29, the pressure side of which is connected by a pipe 30 to a suitable source of compressed air. The flow of air to the diaphragm 55 chamber is controlled by a normally closed, spring pressed, intake valve 31 in a valve casing 32, this valve being operated by a rod 33 extending vertically through the buck and into the padding so as to be depressed by the compression of the padding. The intake valve 31 is coupled with a normally open exhaust valve 34. The bolt 27 is secured to a collar 35 having a square hole therein through which a rod 36 extends, this rod performing the function of the rack 24. When the bolt 60 27 is depressed, it causes the wall of the square hole to bind on the rod 36 and also causes the rod 36 to bind on the walls of the guide passage 37 through which the rod 36 slides.

65 Obviously, when the rod 33 is depressed by the compression of the padding, the exhaust valve 34 will be closed and the intake valve 31 opened, so that air is free to pass from the intake pipe 38 through the valve casing 32 and outlet pipe 39 to the pipe 30 to actuate the diaphragm 28. The 70 75

air pressure on the diaphragm and its movement in response thereto causes the bolt 27 or the collar 35 thereon to lock the bar 36 from sliding movement and hence locks the toggle link 5 12 from swinging movement.

In Figures 6 and 7, the locking of the driven member corresponding to the link 12 is indirectly controlled by the compressing of the pad. In this form of the invention, the yoke lever 4 is pivoted at 5^a in an upwardly movable sliding bearing block 49, the movement of the bearing block upwardly being against the action of a spring 41. Obviously, when the head comes down under pressure on the buck, the pivot of the lever carrying 15 the head tends to move upwardly under the lifting force applied to the rear arm of the lever.

The upward movement of the pivot or bearing block 49 is utilized to operate valves located in the valve casing 42 through suitable motion transmitting parts as levers 43, 44 and a link 45 connecting them. The air passing through the valve casing 42, passes to the diaphragm chamber 29 and operates the bolt 27 as before described. The valve casing 42 and the valves therein are 25 substantially the same as the valve casing 32 with valves 31 and 34 therein.

This invention is particularly advantageous in that a practically uniform pressure is automatically delivered regardless of the thickness of the work and the compression or mashing of the pad within limits and without any attention or adjustments on the part of the operator because the motion transmitting means acts only to the extent necessary to compensate for the compression of the padding. Thereafter the differential mechanism or jaw compressing means delivers its compression movement to the movable jaw and applies substantially uniform pressure because the motor means delivers uniform power 40 and the cam means in having a constant rate of increase or a fixed inclination necessarily delivers uniform pressure. In some instances, with a new thick padding, the differential mechanism may act to almost its full extent and in other cases, it will act very little. It will act between these extremes to various degrees depending upon the thickness of the work or the amount of compression of the padding.

In operation, the operator lays the work on the 50 buck, depresses the push button 9 and the press head closes by the straightening movement of the toggle links 11 and 12. Thereafter, when the head encounters the resistance of the buck, final heavy pressure is applied from motor means 55 7 by the differential or follow-up movement effected by the cam 16 and the follower 17, because the pin 23 locks the rack 24^a to hold the upper link 12 against further rearward travel, but lower link 11 is driven further, as noted in right hand dotted line position, to boost upwardly on link 12 to effect final jaw compression. It will be obvious that the pin 23 also locks the upper link 12 against forward movement which would tend to fold the toggle as the upward pressure 60 exerted by the cam 16 increases.

Compensation for pad wear and diminishing thickness thereof so as to maintain uniform compression of the pad and work is obtained by the 70 feeler head 24 which is mounted under the padding of the buck. This feeler head 24 is sensitive to and detects the contact of the movable pressing element with the upper pad surface and hence as the pad wears and flattens, it follows that the toggle is allowed to straighten further rearwardly to lower the movable pressing element 75

further and further to follow up the gradually thinning padding on the buck.

To open the press, the operator operates the release lever 10, so that the press is free to open under the action of the countersprings 46. 5

What I claim is:

1. In a pressing machine, cooperating pressing elements, one of which is movable toward and from the other, an actuator, motion transmitting means between the actuator and the movable element comprising driving and driven members, differential means connecting the driving and driven members to normally transmit the motion of one directly to the other, and means operable by the pressure between the pressing elements to 15 control the operation of the differential means.

2. In a pressing machine, cooperating pressing elements, one of which is movable toward and from the other, an actuator, motion transmitting means between the actuator and the movable element comprising driving and driven members, normally idle differential means connecting the driving and driven members, means normally locking the differential means from operation, and means controlled by the final pressure movement to release the locking means. 20 25

3. In a pressing machine, cooperating pressing elements, one of which is movable toward and from the other, an actuator, motion transmitting means between the actuator and the 30 movable element comprising driving and driven members, normally idle differential means connecting the driving and driven members, means normally locking the differential means from operation, and means controlled by the final press- 35

ing movement of said elements for locking the driven member from movement with the driving member while the differential means is operated. 40 45

4. In a pressing machine, cooperating pressing

elements, one of which is movable toward and from the other, at least one of the pressing elements being compressible, an actuator, and motion transmitting means between the actuator and the movable element comprising driving and driven members, normally idle differential means 50 connecting them, and means operable by the pressure between the pressing elements to control the operation of the differential means. 55

5. In a pressing machine, cooperating pressing

elements, one of which is movable toward and 50

from the other, one having a compressible pad,

an actuator, motion transmitting means between

the actuator and the movable element comprising

driving and driven members and normally

idle differential means connecting them and ar-

ranged to act during the compressing of the pad,

means for normally locking the differential

means from operation, and means controlled by

the resistance of the pad to the movable ele- 60

ment to release the locking means. 65

6. In a pressing machine, cooperating pressing

elements, one of which is movable toward and

from the other, one having a compressible pad,

an actuator, motion transmitting means be-

tween the actuator and the movable element

comprising driving and driven members and nor-

mally idle differential means connecting them

and arranged to act during the compressing of

the pad, and means controlled by the compres-

sion of the pad to hold the driven member from

movement with the driving member when the

differential means is free to act. 70

7. In a pressing machine, cooperating pressing

elements, one of which is movable toward and

from the other, an actuator, motion transmitting

75

- means between the actuator and the movable element comprising toggle links, the actuator being connected to one link to straighten the toggle, the joint between the toggle links comprising a cam on one link extending at an angle to the straightening movement of the toggle, and a follower on the other link adapted to roll on the cam when the movable pressing element encounters the resistance of the other pressing element.
8. In a pressing machine, cooperating pressing elements, one of which is movable toward and from the other, an actuator, motion transmitting means between the actuator and the movable element comprising toggle links, the actuator being connected to one link to straighten the toggle, the toggle embodying a yielding connection arranged to yield during the straightening of the toggle when the movable element encounters the resistance of the other element, the joint between the toggle links comprising a cam on one link extending at an angle to the straightening movement of the toggle and a follower on the other link movable along the cam when the movable element encounters the resistance of the other element, a lock normally holding the follower and the cam from relative movement one along the other, and means operated by the yielding of said connection for releasing the lock.
9. In a pressing machine, cooperating pressing elements, one of which is movable toward and from the other, one of said elements having a compressible pad, an actuator, motion transmitting means between the actuator and the movable element comprising toggle links, the actuator being connected to one link to straighten the toggle, and the toggle embodying a yielding connection arranged to yield during the straightening of the toggle when the movable element encounters the resistance of the other element, the joint between the toggle links comprising a cam on one link arranged at an angle to the straightening movement of the toggle and a follower on the other link movable along the cam when the movable element encounters the resistance of the other element, a lock normally holding the follower and cam from relative movement one along the other, means operated by the yielding of said connection for releasing the lock, and means operated by the compression of the pad to hold one of the links from swinging movement when the pad compresses.
10. In a pressing machine, cooperating pressing elements, one of which is movable toward and from the other, an actuator, motion transmitting means between the actuator and the movable element comprising driving and driven members, a yielding connection arranged to yield when the movable element encounters a predetermined resistance in its closing movement, a normally idle differential means connecting the driving and the driven members, means normally locking the differential means from movement, and means operated by the yielding of said connection to release the differential locking means.
11. In a pressing machine, cooperating pressing elements, one of which is movable toward and from the other, one of said elements having a yielding pad thereon, an actuator, motion transmitting means between the actuator and the movable element comprising driving and driven members, a yielding connection arranged to yield when the movable element encounters a predetermined resistance in its closing movement, a normally idle differential means connecting the

driving and driven members, means normally locking the differential means for movement, means operated by the yielding of said connection to release the differential locking means, and means controlled by the yielding of the pad to lock the driven member from its normal movement from the driving member when the differential means is acting.

12. In a pressing machine, cooperating pressing elements, one of which is movable toward and from the other, an actuator, motion transmitting means between the actuator and the movable element comprising toggle links, the actuator being connected to one link to straighten the toggle, the joint between the toggle links comprising a cam on one link extending at an angle to the straightening movement of the toggle and a follower on the other link movable along the cam when the movable element encounters the resistance of the other element, a rack extending along the cam, and a pinion meshing with the rack and connected to the cam follower.

13. In a pressing machine, cooperating pressing elements, one of which is movable toward and from the other, an actuator, motion transmitting means between the actuator and the movable element comprising toggle links, the actuator being connected to one link to straighten the toggle, the joint between the toggle links comprising a cam on one link extending at an angle to the straightening movement of the toggle and a follower on the other link being movable along the cam when the movable element encounters the resistance of the other element, a rack extending along the cam, the follower having a pinion meshing with the rack, means normally holding the pinion from rotation, and means operated by the resistance to the closing of the toggle when the movable element presses on the other element to release the holding means.

14. In a pressing machine, cooperating pressing elements, one of which is movable toward and from the other, an actuator, motion transmitting means between the actuator and the movable element comprising toggle links, the actuator being connected to one link to straighten the toggle, the joint between the toggle links comprising a cam on one link extending at an angle to the straightening movement of the toggle and a follower on the other link being movable along the cam when the movable element encounters the resistance of the other element, a rack extending along the cam, the follower having a pinion meshing with the rack, the toggle embodying an endwise compressible section, a spring normally resisting endwise compression of said section, a lock normally holding the pinion from rotation, and connections between said section and the lock to release the latter when the section compresses.

15. In a garment press, a single actuator, and a single power transmitting mechanism between the actuator and a press jaw including a member for operating the latter, said actuator connecting with one end of said member whereby initial closing movement of the press is effected by movement of said end of the member with the actuator and a final pressure of the press is effected by continued movement of the actuator relative to the end of said member, fluid pressure means for operating the actuator, the actuator having means initially forming a positive connection between it and said member to effect the preliminary closing of the press, and cam means on the actuator.

ator acting on said member for transmitting differential movement of the actuator to said member during the final closing of the press and thereby utilizing the substantially full movement of the 5 fluid pressure means in transmitting the motion thereof through a reduced leverage to said member.

16. A garment or ironing press comprising co-operating pressing jaws one of which is movable 10 towards and away from the other, one of the pressing jaws having a resilient mounting, motor means, a toggle connecting the motor means with the movable pressing jaw to close the press to a preliminary closed position, the toggle having a greater extent of movement than necessary to bring the pressing jaws together, locking means 15 operable upon pressure being exerted between the pressing jaws when the movable pressing jaw reaches preliminary closed position and locking the toggle against further movement, and jaw compressing means operatively connecting the motor means with the movable pressing jaw and controlled by the locking of the toggle to apply final jaw compression.

25 17. An ironing or pressing machine comprising co-operating pressing jaws having a compressible pad upon at least one of the jaws, one of the jaws being movable toward and from the other, an actuator, motion transmitting means between the actuator and the movable jaw to close the press, including initial closing means and final jaw compressing means cooperating with the initial closing means and producing pressure between the pressing jaws, and means controlled by the movement of the compressible pad when the pressing jaws engage for controlling the actuation of the jaw compressing means.

40 18. An ironing or pressing machine comprising co-operating pressing jaws having a compressible pad upon at least one of the jaws, one of the jaws being movable toward and from the other, an actuator; motion transmitting means between the actuator and the movable jaw to close the press, including initial closing means which operate until the pressing jaws engage, the initial closing means having a movable member, and jaw compressing means connected with the actuator and impelling the movable member substantially longitudinally for producing pressure between the pressing jaws; and means controlled by the movement of the compressible pad when the pressing jaws engage for holding the movable member against any pivotal movement other than that needed to obtain substantially only longitudinal movement thereof and thereby controlling the actuation of the jaw compressing means.

45 19. An ironing or pressing machine comprising co-operating pressing jaws having a compressible pad upon at least one of the jaws, one of the jaws being movable toward and from the other, an actuator, motion transmitting means to close the press connected between the actuator and the movable pressing jaw; the motion transmitting means including initial closing means which operate until the pressing jaws engage, the initial closing means having a member which pivots substantially during the initial closing movement, and jaw compressing means co-operating with the pivoted member of the initial closing means to move the same substantially

longitudinally with only such pivotal movement as is necessary to obtain the longitudinal movement; and means controlled by the movement of the compressible pad when the pressing jaws engage for holding the pivoted member against the aforesaid substantial pivotal movement other than that necessary to obtain substantially only longitudinal movement thereof and thereby controlling the actuation of the jaw compressing means.

10 20. A garment or ironing press comprising co-operating pressing jaws one of which is movable towards and away from the other, one of the pressing jaws having a resilient mounting, motor means, motion transmitting means connecting the motor means with the movable pressing jaw including initial closing means to close the press to a preliminary closed position with the jaws in contact, the initial closing means having a greater extent of movement than necessary to bring the pressing jaws together, means operable upon pressure being exerted between the pressing jaws when the movable pressing jaw reaches preliminary closed position for locking the initial closing means against further operation, and jaw compressing means operatively connected between the motor means and the movable pressing jaw and controlled by the locking of the initial closing means to apply final jaw compression.

15 21. A garment or ironing press comprising co-operating pressing jaws one of which is movable towards and away from the other, one of the pressing jaws having a resilient mounting, motion transmitting means connected with the movable pressing jaw including initial closing means to close the press to a preliminary closed position, the initial closing means having a greater extent of movement than necessary to bring the pressing jaws together, locking means operable upon pressure being exerted between the pressing jaws when the movable pressing jaw reaches preliminary closed position and locking the initial closing means against further operation, a single motor, and jaw compressing means carried by the initial closing means and operatively connected with the motor whereby the initial closing means is operated through the connection with the motor and the jaw compressing means becomes operable to apply final jaw compression by the locking of the initial closing means.

20 22. A garment or ironing press comprising co-operating pressing jaws one of which is movable towards and away from the other, one of the pressing jaws having a resilient mounting, a toggle connected with the movable pressing jaw to close the press to a preliminary closed position, the toggle being in bent position at all times irrespective of mashing of the resilient mounting and the thickness of the work, locking means operable upon pressure being exerted between the pressing jaws when the movable pressing jaw reaches preliminary closed position for locking the toggle against further closing movement, a single motor, and jaw compressing means carried by the toggle and operatively connected with the motor whereby the toggle is operated through the connection of the motor therewith and the jaw compressing means is operated to apply final jaw compression by the locking of the toggle.
